UNITED STATES PATENT OFFICE

OSCAR J. MUTSCHL, OF TOLEDO, OHIO, ASSIGNOR TO THE DE VILBISS COMPANY, OF
TOLEDO, OHIO, A CORPORATION OF OHIO

ATOMIZER

Application filed May 6, 1929. Serial No. 360,628.

This invention relates to a spraying device especially adapted to be used in connection with a bottle or similar receptacle containing perfume, a medicinal preparation or the like.

One of the objects of the invention is to provide such a receptacle with a top having a tapered bore fitted with a stopper which is automatically held therein with a predetermined pressure. Another object is to provide a stopper which acts as a valve and which is rotatably adjustable to render the spraying device operable, or to cut off the fluid outlet and the air supply, as well as the air vent, to prevent possible spilling or evaporation of the contents of the receptacle when the atomizer is not in use.

The above and other characteristic features of the invention will be more specifically explained with reference to the accompanying drawings, in which

Figure 1 is a central longitudinal section illustrating one embodiment of the invention.

Figure 2 is a section taken on the line 2—2 of Figure 1.

Figure 3 is a central longitudinal section illustrating another embodiment of the invention.

Figure 4 is a section taken on the line 4—4 of Figure 3.

As illustrated in Figures 1 and 2, the invention is associated with a receptacle 5 having a metallic collar 6 in which a top 7 is removably secured. This top is formed with an upwardly tapered vertical bore 8 which forms a seat for a correspondingly tapered stopper 9. The upper or smaller end portion of the stopper 9 extends some distance above the top 7, where it is formed with a reduced threaded end to which a head 10 is secured. The head 10 is formed with a sleeve 11 which extends downwardly substantially to the surface of the top 7 and is spaced from the upper portion of the stopper 9, to provide a housing for a coil spring 12 which acts between the head 10 and the top 7 to urge the stopper upwardly into close fitting relation to the seat 8.

The lower end of the stopper 9 is extend-

ed downwardly into the receptacle to form a sleeve 13 in which a liquid supply tube 14 is secured. The stopper 9 is formed with a liquid passageway 15, constituting a continuation of the passageway through the tube 14 and having a lateral outlet 16 which is adapted to register with a similar passage 17 leading through the top 7 into a laterally disposed nozzle 18 having an outlet 19.

Air pressure for inducing a flow of liquid to the nozzle 18 and discharging it in the form of spray is supplied from an air chamber formed by securing a diaphragm 20 of rubber or the like to the head 10. An air supply passage 21 leads from this chamber through the stopper 9. This passageway 21 has a laterally disposed outlet 22 adapted to register with the passageway 23 through an air supply member which is in alignment with the discharge orifice 19.

When the diaphragm 20 is depressed, air is forced through the passageway 21 and induces a flow of liquid through the tube 14, which is discharged from the orifice 19 in the form of spray. As soon as the diaphragm 20 is released, the air chamber is refilled with air drawn through ports 24 in the sleeve 11 and past a ball check valve 25 in the head 10.

The stopper 9 is also provided with an air vent passageway 27, which is adapted to register with a passageway 26 through the head 7 to admit air to the receptacle 5 and maintain normal atmospheric pressure within the receptacle.

The stopper 9 constitutes a valve for controlling the operation of the atomizer. In the position shown in Figure 1 the liquid outlet passageway, the air supply passageway and the air vent passageway are all in open or operative position. All of these passageways may be cut off, however, by rotating the valve or stopper 9 through a small angle. Provision is made for limiting such rotation to an angle of approximately 90°. For this purpose, a plug 28 is provided in the top 7 and has an inward extension 29 projecting into an arcuate channel 30 formed in the stopper 9.

In the embodiment of the invention, shown

in Figures 3 and 4, a receptacle 31 is provided with a collar 32, to which a top 33 is threaded or otherwise secured. The top 33 is formed with a vertical upwardly tapered bore 34, forming a seat to receive a correspondingly tapered stopper 35. A head 36 is secured to the upwardly projecting end of the stopper 35 and is formed with a sleeve 37 constituting a housing for the spring 38, which acts in the same manner as the spring 12 in Figure 1.

A downwardly extending sleeve 39 is secured in the lower end of the stopper 35 and has a liquid supply tube 40 secured therein. The liquid from the receptacle 31 is supplied through the tube 40 and passageway 41 and thence through a branch passageway 42 in the stopper. This branch passageway normally registers with a passageway 43 leading to a nozzle 44 which extends laterally from the head 33 and is provided with a discharge orifice 45.

Air under pressure is supplied to the orifice 45 through a passageway 46 in the top 33, which normally registers with an air supply passageway 47 through the stopper 35. The air is supplied to the passageway 46 through a tube 48 having a nipple 49 secured to its outer end and adapted to be connected with a bulb or other suitable source of air pressure.

The top 33 is also provided with an air vent passageway 50 normally registering with a passageway 51 leading through the stopper 35 into the upper end of the receptacle 31.

The stopper 35 also acts as a valve which may be rotated in the same manner as the stopper 9 in Figure 1 to cut off the air and liquid supply passages as well as the air vent passage. For limiting the rotation of the stopper 35, the head 36 is provided with a lug 52 projecting downwardly into an arcuate channel 53 formed in the upper face of the top 33.

From the foregoing description, it will be seen that the invention provides a receptacle with a top having a tapered seat against which the stopper is automatically held to prevent leakage. This stopper, however, may be loosened by downward pressure, whenever it is desired to adjust the same circumferentially. In normal position, the stopper or valve freely opens the passageways from the liquid supply, the air pressure supply, and the air which is supplied to the receptacle to maintain atmospheric pressure therein. All these passageways, however, may be cut off simultaneously by a partial rotation of the valve or stopper.

While I have described specifically the various features of the invention as embodied herein, it will be understood that the invention is not limited thereto but includes all

such modifications as may fall within the scope of the appended claims.

What I claim is:

1. In an atomizer, a receptacle having a top with a bore tapering upwardly to constitute a seat, a correspondingly tapered stopper cooperating therewith and projecting upwardly above said top, a head secured to the upper end of the stopper, and a spring acting between said head and said stopper to hold the stopper against its seat, said top being provided with a liquid outlet passage, an air supply passage and an air vent passage all intersecting said bore, said stopper being rotatable through a limited angle and having means to open or cut off all of said passages.

2. In an atomizer, a receptacle provided with a top having an upwardly tapered bore therein, a correspondingly tapered stopper seated in said bore, means including a spring for constantly urging the stopper against its seat, said top and stopper having a liquid outlet passage, an air supply passage and an air vent passage therethrough, all of said passages being normally open, said stopper constituting a valve and having a limited rotational adjustment to cut off all of said passages and thereby prevent possible escape of the contents of the receptacle by leakage or evaporation.

3. In an atomizer, a receptacle provided with a top having an upwardly tapered bore therethrough, a correspondingly tapered stopper seated in said bore with its small end projecting beyond the same, a housing secured to said small end, a spring within the housing acting between said housing and the top of the receptacle to urge the stopper constantly against its seat, said top and stopper having a liquid outlet passage, an air supply passage and an air vent passage therethrough, all of said passages being normally open, said stopper constituting a valve and having a limited rotational adjustment to cut off all of said passages and thereby prevent possible escape of the contents of the receptacle by leakage or evaporation.

4. In an atomizer, a receptacle having a top with a bore tapering upwardly to constitute a seat, a correspondingly tapered stopper cooperating therewith and projecting upwardly above the top, a head secured to the upper end of the stopper, and a spring acting between said head and stopper to hold the stopper against its seat, said top being provided with an air vent passage, a straight, substantially horizontal diametric passage through the top constituting an air pressure supply passage, and a liquid passage having an outlet concentric with the air passage outlet, said stopper being partially rotatable to cut off all of said passages.

5. In an atomizer, a container provided

- with a top having an upwardly tapered bore, an upwardly tapered stopper seated in said bore, a spring urging said stopper against its seat, a nozzle extending laterally from said top, air pressure supply means including an air supply duct leading through said top to the nozzle, said top being formed with a liquid passageway leading from said bore to the nozzle and with an air vent leading from the bore to the atmosphere, the discharge end of said liquid passageway being coaxial with the discharge end of the air supply duct, said stopper being provided with passageways which lead from the interior of the container to said liquid passageway and said air vent respectively when the atomizer is in position for operation, and means for rotatively adjusting said stopper to cut off said liquid passageway and said air vent.
- 20 6. In an atomizer, a receptacle having a top with a bore tapering upwardly to constitute a seat, a correspondingly tapered stopper cooperating therewith and projecting upwardly above said top, a head secured to the upper end of the stopper, and a spring acting between said head and said stopper to hold the stopper against its seat, said top being provided with a liquid outlet passage and an air supply passage, both intersecting said bore, said stopper being rotatable through a limited angle to open or close both of said passages.
- 25 30 35 In testimony whereof I have hereunto signed my name to this specification.

OSCAR J. MUTSCHEL.
